NESTING CART

Samu-El Ish-Shalom, New York, N. Y.

Application July 29, 1950, Serial No. 11,483

Term of patent 14 years

(Cl. D14—3)

To all whom it may concern:

Be it known that I, Samu-El Ish-Shalom, a citizen of the United States, residing at New York, N. Y., have invented a new, original, and ornamental Design for Nesting Cart, of which the following is a specification, reference being had to the accompanying drawing, forming a part hereof.

Figure 1 is a perspective view of a nesting cart, showing my new design;

Figure 2 is a side elevational view of the cart; and

Figure 3 is an end elevational view of the cart.

I claim:

The ornamental design for a nesting cart, substantially as shown.

SAMU-EL ISH-SHALOM.
